by J. G. Roberts Atty

UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,263,069.

Specification of Letters Patent. Patented Apr. 16, 1918.

Application filed July 12, 1917. Serial No. 180,117.

To all whom it may concern:

Be it known that I, CHARLES W. KECKLER, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone exchange systems and has for its object the production of such a system in which it is impossible for an operator to listen in on a connection established between two telephone lines and in which it is impossible 15 to establish a connection between two telephone lines using portions of two connecting circuits.

In accordance with a feature of this invention, a central office connecting circuit 20 joining two telephone lines is provided with means whereby, when an operator controlled switch is actuated to connect an operator's telephone set with one end of the connecting circuit, the other end is thereupon short-circuited.

In accordance with another feature of this invention, the connecting circuits are provided with means whereby, when two operator controlled switches of different connecting circuits are simultaneously actuated, 30 relays of the connecting circuit coöperate to establish a disabling circuit for the operator's telephone set.

For a more complete understanding of 35 this invention, reference should be had to the following description considered in connection with the accompanying drawing, wherein Figure 1 shows a telephone exchange system containing one embodiment 40 of this invention; and Fig. 2 shows a modified form thereof.

In Fig. 1 there are shown two telephone lines A and B, which extend from subscribers' stations to a central office, at which is 45 located a cord circuit C employed for connecting together the two telephone lines. For convenience only, these two lines and the one cord circuit are shown but it is to be understood that many such lines and several such cord circuits may be and usually 50 are provided in the same central office.

Assuming that the answering end of the cord circuit C is connected with the answering jack of telephone line A, that the calling 55 plug of cord circuit C is connected with the

answering jack of line B, and that the operator wishes to converse with subscriber B, listening key 5 is actuated to connect the operator's telephone set with the calling end of the cord circuit C and the answering end 60 thereof is simultaneously short-circuited. The circuit including the operator's telephone set established by the actuation of the listening key 5, may be traced from the tip conductor of the calling plug 6 through 65 the tip talking strand 7, conductor 8, contact 9, conductors 10 and 11, the operator's telephone set, conductor 12, contact 13, portion 14 of the ring talking strand, contact 15 of listening key 16, portion 35 of the 70 ring talking strand to the ring contact of the calling plug 6. The short circuit for the answering end of the cord circuit established by the actuation of key 5, may be traced from the point 80 on the tip talking 75 strand through the contact 25 of the listening key 5 to the point 81 on the ring talking strand. It will be observed that battery for talking purposes is now fed through the double wound retardation coil 27 to the calling 80 end of the cord circuit. Relay 30 associated with cord circuit C is energized upon the actuation of the listening key 5 and co-operates with a similar relay of another cord circuit when energized to establish a short 85 circuit for the operator's telephone set, as will hereinafter more fully appear.

Should the operator desire to converse with subscriber A rather than subscriber B, the listening key 16 instead of 5 is actuated to thereby connect the operator's telephone set with the answering end of the cord circuit and to simultaneously establish a short circuit for the calling end thereof. The circuit including operator's telephone 90 set, established by the actuation of the listening key 16, may be traced from the tip contact of the answering plug 4, tip talking strand 7, contact 31 of the listening key 16, conductors 10 and 11, the operator's telephone set, conductor 12, contact 32 of the listening key 16, portion 14 of the ring talking strand, contact 33 of the listening key 5, portion 26 of the ring talking strand 100 to the ring contact of the answering plug. With this condition of the cord circuit, the battery for talking purposes is fed through the double wound retardation coil 27 to the answering end. The short circuit for the calling end of the cord circuit established 105 110

by the actuation of the listening key 16, may be traced from the point 82 on the tip talking strand through the contact 34 of the listening key 16 to the point 83 on the 5 ring talking strand. Relay 30 is also operated upon the actuation of the listening key 16.

Between the lines 2-2 and 3-3 in Fig. 1, there is shown a relay 40 similar in all 10 respects to relay 30, which is associated with another cord circuit and is actuated when either of the listening keys of this other cord circuit is actuated. Below the line 3-3 in Fig. 1, there is shown another 15 relay 50 similar to relays 30 and 40, which is associated with a third cord circuit similar to the cord circuit C.

If the answering end of cord circuit C be connected with one telephone line and 20 the answering end of another cord circuit with which relay 40 is associated be connected to another telephone line and an attempt be made to connect these lines together by actuating one of the listening 25 keys in each cord circuit, the lines are not thereby connected telephonically together but the operator's telephone set is immediately short-circuited. This is brought about by the energization of relays 30 and 30 40 when a listening key of cord circuit C and a listening key of the cord circuit with which relay 40 is associated are actuated. The short circuit for the operator's telephone set may be traced from a point 41 through conductor 42, contact 43 of relay 30, contact 44 of relay 40, and contact 45 of relay 30 to a point 46. If relay 50 instead 35 of 40 had been energized at time relay 30 was energized, the short circuit for the operator's telephone set established thereby, 40 would be from the point 41 through conductor 42, contact 43 of relay 30, contact 47 of relay 40, contact 48 of relay 50, and contact 45 of relay 30 to the point 46.

45 In Fig. 2 there is shown a cord circuit provided with apparatus for short-circuiting one end of the cord circuit whenever the operator's telephone set is associated with the other end. In this cord circuit, the number of key contacts has been reduced and the connection of the operator's telephone set to one end of the cord circuit and the simultaneous short-circuiting of the other end is effected through the operation 50 of relays controlled by single contact keys.

55 Referring further to the cord circuit of Fig. 2 and assuming that the answering end thereof is connected with the answering jack of line A, that the calling end is connected with the answering jack of line B, and that the operator wishing to converse with subscriber B actuates key 51, relay 53 is thereupon energized. The energization 60 of relay 53 causes this relay to open its normal contact 54 and to connect the oper- 65

ator's telephone set through its left-hand alternate contacts 57 and 58 to the calling end of the cord circuit. The closure of the right alternate contact of relay 53 establishes a short circuit for the answering end 70 of the cord circuit. The circuit including the operator's telephone set may be traced from the tip contact of calling plug 66 through the tip talking strand 67, right-hand alternate contact of relay 53, right-hand normal contact of relay 55, portion 75 56 of the ring talking strand, contact 57 of relay 53, the operator's telephone set, contact 58 of relay 53, and portions 59 and 68 of the ring talking strand to the ring 80 contact of the calling plug 66. The short circuit for the answering end resulting from the actuation of the key 51 may be traced from the point 70 on the tip talking strand through the right-hand alternate contact to 85 relay 53, and the right-hand normal contact of relay 55 to the point 71 on the ring talking strand. Battery for talking purposes is now fed to the calling end of the cord circuit through the double wound retardation coil 61 and the left-hand normal contact of relay 55.

If the operator desires to converse with subscriber A instead of subscriber B, key 52 instead of 51 is actuated. The actuation 95 of key 52 causes the energization of relays 53 and 55, thereby connecting the operator's telephone set with the answering end of the cord circuit and simultaneously short-circuiting the calling end thereof. The circuit including the operator's telephone set may be traced from the tip contact of the answering plug 64 through the tip talking strand 67, right-hand alternate contact of relay 53, right-hand alternate contact of relay 55, the portion 59 of the ring talking strand, contact 58 of relay 53, the operator's telephone set, contact 57 of relay 53, and portions 56 and 60 of the ring talking strand to the ring contact of the answering plug 64. The short circuit for the calling end may be traced from the point 70 on the tip talking strand through the right-hand alternate contact of relay 53, and the right-hand alternate contact of relay 55 to the point 72 on the ring talking strand. Battery for talking purposes is now fed to the answering end of the cord circuit through the double wound retardation coil 61 and the left-hand alternate contact of relay 55. 110

115 Below the line 1-1 of Fig. 2 there is shown a portion of the control apparatus including the two relays of another cord circuit which controls the connection of the operator's telephone set to one end thereof 120 while the other end is simultaneously short-circuited.

125 What is claimed is:

1. A telephone exchange system comprising two telephone lines, a connecting cir- 130

- cuit joining the lines, an operator's telephone set, an operator controlled switch actuated to connect the operator's telephone set with one end of the connecting circuit, 5 and a short circuit for the other end of the connecting circuit established upon the actuation of the switch.
2. A telephone exchange system comprising two telephone lines, a connecting circuit joining the lines, an operator's telephone set, a listening key actuated to connect the operator's telephone set with one end of the connecting circuit, and a short circuit for the other end of the connecting circuit established by the actuation of the listening key and including a contact thereof.
3. A telephone exchange system comprising telephone lines terminating at a central office, connecting circuits thereat for interconnecting the lines, an operator's telephone set, an operator-controlled switch for each connecting circuit adapted when actuated to cause the connection of an operator's telephone set with the corresponding connecting circuit, a relay for each connecting circuit operating upon the actuation of the associated switch, and a disabling circuit for the operator's telephone set established upon the simultaneous operation of two relays.
4. A telephone exchange system comprising telephone lines terminating at a central office, connecting circuits thereat for interconnecting the lines, an operator's telephone set, a listening key for each connecting circuit adapted when actuated to connect the operator's telephone set with the connecting circuit, a relay for each connecting circuit energized upon the actuation of the asso-
- ciated listening key, and a short circuit for 40 the operator's telephone set established by the simultaneous energization of two relays and including contacts of both relays.
5. A telephone exchange system comprising telephone lines terminating at a central 45 office, connecting circuits thereat for interconnecting the lines, an operator's telephone set, an operator controlled switch for each connecting circuit adapted when actuated to connect the operator's telephone set with 50 one end of the associated connecting circuit, a short circuit for the other end of the associated connecting circuit established upon the actuation of the switch, a relay for each connecting circuit operating upon the 55 actuation of the switch associated therewith, and a disabling circuit for the operator's telephone set established upon the simultaneous operation of two relays.
6. A telephone exchange system comprising telephone lines terminating at a central 60 office, connecting circuits thereat for interconnecting the lines, an operator's telephone set, a listening key for each connecting circuit actuated to connect the operator's telephone set with one end thereof, a short circuit for the other end of the connecting circuit established by the actuation of the listening key and including a contact thereof, a relay for each connecting circuit energized upon the actuation of the listening key, and a short circuit for an operator's telephone set established by the simultaneous energization of two relays and including contacts of both relays.

In witness whereof I hereunto subscribe my name this 9th day of July, A. D. 1917.

CHARLES W. KECKLER.
